UNITED STATES PATENT OFFICE.

HARRY J. ANDERSON, OF CHICAGO, ILLINOIS, ASSIGNOR TO NEWMAN BROS. CO., OF CHICAGO, ILLINOIS.

MECHANICAL MUSICAL INSTRUMENT.

1,062,944.

Specification of Letters Patent. Patented May 27, 1913.

Application filed May 13, 1911. Serial No. 826,985.

To all whom it may concern:

Be it known that I, HARRY J. ANDERSON, a citizen of the United States, residing at Chicago, in the county of Cook and State 5 of Illinois, have invented a certain new and useful Improvement in Mechanical Musical Instruments, of which the following is a full, clear, concise, and exact description, reference being had to the accompanying 10 drawings, forming a part of this specification.

This invention is an improved construction of the pneumatic actions of musical instruments, and has been devised more especially 15 for use in self playing instruments and in piano players.

The invention is fully set forth in the specification given below, and it consists in the novel construction of parts and devices 20 and novel combinations of parts and devices hereinafter described.

In the accompanying drawings Figure 1 is a plan view of the board carrying the valves and valve seats, part being broken away; 25 Fig. 2 is a cross sectional view on the line 2—2 of Fig. 1, also showing a connection board in place above the valve board; Fig. 3 is an elevational view showing a number of tiers of pneumatics mounted in position, 30 this figure being taken from the left of Fig. 2; Fig. 4 is a cross section taken on the line 4—4 of Fig. 3, showing the manner of assembling the pneumatics in tiers and also showing the main wind chest, and the primary 35 and secondary passages leading therefrom.

In said drawings 1—1 are the usual pneumatics for actuating key striking devices 2—2. Said pneumatics connect by means of 40 a passage-way 3 with a valve chest 4. Mounted in chest 4 are valves 5, governing seats 6 and 7 controlling respectively the passages leading to the atmosphere and to a suction wind chest, said suction wind chest 45 being designated as 8. Said seats 6 and 7 are the extremities of struck up metal plates 6^a and 7^a which have annular flanges for attaching the plates to the body of the apparatus, and dished portions extending toward 50 the valve and then upset so as to leave a fairly sharp but smooth seat. Valves 5 carry depending stems 9 having heads which contact with diaphragms 10 for controlling the position of the valves 5. These valves 55 also have upwardly extending stems 9^a,

stems 9 and 9^a both having guide pieces 23 and 24. The space below the diaphragm 10 is normally exhausted of air by means of a pin hole in said diaphragm and is in direct connection with a passage 11 leading to the atmosphere but normally closed by means of a primary valve 12. The primary valves 12 are also controlled by pneumatic action, there being a stem 13 depending from each valve, contacting with a diaphragm 14 in 60 chamber 14^a. Diaphragm 14 is normally depressed as in the case of diaphragm 10, there being a passageway 15 leading from below diaphragm 14 to tube 16, passageway 17 in bleed chest 18 to tube 19 which 65 connects with the usual tracker board. A connection exists between the wind chest 8 and chamber 14^a indicated in dotted lines in Fig. 2 and shown in plan in the broken away portion of Fig. 1. The passages 17 are 70 normally exhausted through pin hole openings in disks 25 which cover the opening between the passage 17 and a slot 26 in a strip 27 which is attached to the board 18 and runs across the ends of the passages 17, placing them all in connection with a passageway 28 which leads through the end of the board 18 to a connection with passageway 32.

In the operation of this device when an 85 opening in the music roll corresponding to any tube 19 places such tube in connection with the atmosphere, atmospheric pressure is introduced beneath the diaphragm 14 disturbing the equilibrium of said diaphragm 90 causing it to lift and thereby open valve 12. Atmospheric pressure is thus introduced below diaphragm 10 and valve 5 is accordingly operated to close the connection between pneumatic 1 and the atmosphere and 95 open the connection between the pneumatic and the suction in chest 8, thus operating the pneumatic and key striking mechanism. Wind chest 8 is maintained at a low pressure by connection to an ordinary bellows 100 which is made through tube 30.

Particular attention is called to the arrangement of valves by which both the primary valve 12 and the secondary valve 5 are carried by the same board 20, and also 105 to the construction of the valve 5 with its accompanying stems and guide plates, and also the arrangement of seats for said valves. Immediately below the board 20 is a second board 21, to which the pneumatics are di- 110

rectly attached. Boards 20 and 21 are separated by strips such as 22, 23, and 24 running longitudinally thereof and serving to form the suction wind chest 8 and the chamber 14 in the space between the two boards.

Referring more particularly to Figs. 3 and 4, it is seen that in accordance with my construction the pneumatics are arranged in tiers in such a manner that they are rigidly attached together into one structure, so that they may be handled and installed as a unit. At the same time the structure may be readily taken apart for inspection or repair. The structure is also cheaply manufactured and readily assembled. As shown in Fig. 3 the boards 20 and 21 are wider than necessary to accommodate the width of the pneumatics. Along the edge so formed blocks 31 are inserted of a thickness sufficient to allow for the depth of the pneumatics. Blocks 31 are wedge shaped as shown in Fig. 4, so that the complete unit composed of blocks 31, 21, 22 and 20 presents a horizontal surface for the attachment of the next succeeding tier of pneumatics. The several tiers of pneumatics, together with the board 18 above referred to are then connected together by one or more bolts such as 33, uniting them into a rigid structure.

Shown below the pneumatics is a wind chest 36 carried on a metal plate 35, which in turn rests upon the frame of the piano. The pneumatics are fastened to the chest 36 by means of bolts 34 passing through the various tiers of pneumatics and the wind chest into the plate 35. The chest and pneumatics are then secured to the piano by means of lag screws such as 39. The chamber within the chest is designated as 37. This connects with the bellows on the one hand by the opening 38, and with the various individual wind chests 8, by the passageway 30, while the chambers 14^a and the passage 26 are connected to 37 by means of the passage 32.

It will be seen that two ways are shown of connecting the windway 14^a with the suction, one through passage 32 and the other through passage 30, windway 8 and the passage shown in Fig. 1. One or the other of these connections may be omitted if desired.

It will be understood that while the construction shown and described in this specification is the preferred form of my inven-

tion, modifications may be made without departing from the spirit of my invention.

What I claim as new and desire to secure by Letters Patent is:

1. In a device of the class described, a plurality of tiers of pneumatics, valves for said pneumatics, mechanism for operating said valves, a bleed chest mounted above the top tier of pneumatics, having a plurality of passages therein, having an outlet from each of said passages adapted to be connected to a tracker board and an outlet leading to said valve operating mechanism, a member provided with a groove carried by said bleed chest and disks having restricted openings which communicate with said passages and said groove.

2. In a device of the class described in combination, an action chest comprising top and bottom boards, a row of pneumatics attached to the bottom board of said chest, valves for said pneumatics mounted on the top board of said chest, mechanism for operating said valves and a bleed chest mounted immediately above said top board but spaced therefrom, said bleed chest having transverse passages each of which is provided with an outlet for connection with a tracker board, and also with an outlet for connection to the mechanism for operating said valves, said mechanism being mounted on said bottom board of the action chest.

3. In a device of the class described in combination, a structure having a wedge shaped piece with its inclined face upward, a second wedge shaped piece with its inclined face resting against the inclined face of the first mentioned piece, said second wedge being extended laterally of the structure, and having a plurality of pneumatics attached to its inclined surface, and a substantially rectangular block above said second mentioned piece having primary and secondary valves mounted thereon, said rectangular block being spaced from said second mentioned piece by spacing strips whereby windways are formed for said valves and said pneumatics.

In witness whereof, I hereunto subscribe my name this 28th day of April A. D., 1911.

HARRY J. ANDERSON.
